(57) **CLAIM**

The ornamental design for a front cover for an engine, as shown and described.

DESCRIPTION

FIG. 1 is a front elevation view of a front cover for an engine;

FIG. 2 is a back elevation view of a front cover for an engine;

FIG. 3 is a top elevation view of a front cover for an engine;

FIG. 4 is a bottom view of a front cover for an engine;

FIG. 5 is a right side view of a front cover for an engine;

FIG. 6 is a left side view of a front cover for an engine;

FIG. 7 is a bottom perspective view of a front cover for an engine;

FIG. 8 is a top perspective view of a front cover for an engine;

FIG. 9 is an additional bottom perspective view of a front cover for an engine; and,

FIG. 10 is an additional top perspective view of a front cover for an engine.

The dashed lines shown depict the environment and represent unclaimed subject matter and form no part of the claimed design.

1 Claim, 10 Drawing Sheets
